DESIGN FOR A CARPET.

Design No. 12,518, dated October 11, 1881.

UNITED STATES PATENT OFFICE.

CHARLES MAGEE, OF WILLIAMSBURG, NEW YORK, ASSIGNOR TO THE BIGELOW CARPET COMPANY, OF CLINTON, MASSACHUSETTS.

DESIGN FOR A CARPET.

SPECIFICATION forming part of Design No. 12,518, dated October 11, 1881.

Application filed August 30, 1881. Term of patent 3½ years.

To all whom it may concern:

Be it known that I, CHARLES MAGEE, of Williamsburg, in the county of Kings and State of New York, have invented a new and original Design for Carpets, of which the following is a specification.

This invention relates to a new and original design for carpets, oil-cloths, and similar fabrics.

10 It consists in the novel grouping and configuration of parts hereinafter more fully described.

The accompanying photograph illustrates a face view of a carpet having my new design.

15 The carpet is by a central stripe divided into two prominent parts, A and B. The part B is by a further stripe divided into two bands, *i* and *h*. The band *i* has a series of lyre-shaped ornaments, and the band *h* contains series of 20 branches with flowers and buds thereon, as shown. The groundwork of the part *h* has vertical lines, that do not, however, extend quite to its lower edge. The lower part of the stripe *h* is undulating, and below it is a band filled

25 with vertical bars. The part A contains a cravat-shaped figure having a central portion, *e*, five-sided in form, with wings *f* and *c* thereon, as shown. Between the wings *f* and *c* of every two of these cravat-shaped ornaments is an angular figure, *b*, embracing a pentagonal figure, *a*. The lower part of the portion A is bounded

by a border, *g*, containing a row of geometrical figures, as shown.

I claim—

1. The design for carpets, consisting of the 35 band *i*, ornamented substantially as shown.

2. The design for carpets, consisting of the band *h*, ornamented substantially as shown.

3. The design for carpets, consisting of the part B, having bands *h* and *i*, substantially as 40 shown.

4. The design for carpets, consisting of the figure *e*, and wings *f* and *c* thereon, substantially as shown.

5. The design for carpets, consisting of the 45 figures *e*, *f*, *c*, *b*, and *a*, substantially as shown.

6. The design for carpets, consisting of the figures *e f c b a* and border *g*, substantially as shown.

7. The design for carpets, consisting of the 50 figures *e*, *f*, *c*, *b*, *a*, and *h*, substantially as shown.

8. The design for carpets, consisting of the figures *e*, *f*, *c*, *b*, *a*, *h*, and *i*, substantially as shown.

9. The design for carpets, consisting of the 55 figures *e*, *f*, *c*, *b*, *a*, *g*, *h*, and *i*, substantially as shown.

CHARLES MAGEE.
